UNITED STATES PATENT OFFICE.

FLOYD F. CARY, OF FAIRHAVEN, MASSACHUSETTS, ASSIGNOR TO THE PAIRPOINT CORPORATION, A CORPORATION OF MASSACHUSETTS.

DESIGN FOR A GLASS PLATE OR SIMILAR ARTICLE.

50,551.

Specification for Design.

Patented Apr. 3, 1917.

Application filed October 30, 1916. Serial No. 128,625. Term of patent 7 years.

To all whom it may concern:

Be it known that I, FLOYD F. CARY, a citizen of the United States, residing at Fairhaven, in the county of Bristol and State of Massachusetts, have invented a new, original, and ornamental Design for a Glass Plate or Similar Article, of which the following is a specification, reference being had to the accompanying drawing, forming a part thereof.

In the drawing the figure is a plan view of a glass plate illustrating my new design.

The design comprises a principal central figure A, representing an urn with draping of leaves depending from its handles. This

central figure is inclosed within a circle, outside of which are radial figures B, extending to an outer circle C around which are grouped panels D, and intervening urns E and spacing ornaments G all blended together to form an artistic design.

What I claim is:

The ornamental design for a glass plate or similar article as shown and described.

FLOYD F. CARY.
